CLAIM

The ornamental design for an audio cassette storage and display rack, as shown and described.

DESCRIPTION

FIG. 1 is a perspective view of an audio cassette storage and display rack showing our new design;

FIG. 2 is a top plan view thereof;

FIG. 3 is a bottom plan view thereof;

FIG. 4 is a front elevational view, the rear elevation view being the same;

FIG. 5 is a right side elevational view of FIG. 2, the left side being the same;

FIG. 6 is a sectional view taken on line 6—6, FIG. 2; and,

FIG. 7 is a sectional view taken on line 7—7, FIG. 2.
